CLAIM

The ornamental design for furniture controller as shown and described herein.

DESCRIPTION

FIG. 1 is a perspective view of a first embodiment of a furniture controller according to the present invention.

FIG. 2 is a top view of FIG. 1.

FIG. 3 is a bottom side view of FIG. 1.

FIG. 4 is a top side view of FIG. 1.

FIG. 5 is a left side view of FIG. 1, the right side view being substantially the same.

FIG. 6 is a perspective view of a second embodiment of a furniture controller according to the present invention.

FIG. 7 is a top view of FIG. 6.

FIG. 8 is a bottom side view of FIG. 6.

FIG. 9 is a top side view of FIG. 6; and,

FIG. 10 is a left side view of FIG. 6, the right side view being substantially the same.

The broken lines shown in FIGS. 1-10 are for the purposes of illustrating environmental structure and form no part of the claimed design.

1 Claim, 6 Drawing Sheets
